(57) **CLAIM**

The ornamental design for a divided food dish, as shown and described.

DESCRIPTION

FIG. 1 is a top, front and right side perspective view of a first embodiment of a divided food dish showing my new design; FIG. 2 is a bottom, rear and right side perspective view thereof;

FIG. 3 is a top plan view thereof;

FIG. 4 is a bottom plan view thereof;

FIG. 5 is a front elevation view, the rear elevation view being identical thereto;

FIG. 6 is a right side elevation view, the left side elevation being identical thereto;

FIG. 7 is a top, front and right side perspective view of a second embodiment of a divided food dish showing my new design;

FIG. 8 is a bottom, rear and right side perspective view thereof;

FIG. 9 is a top plan view thereof;

FIG. 10 is a bottom plan view thereof;

FIG. 11 is a front elevation view thereof;

FIG. 12 is a rear elevation view thereof;

FIG. 13 is a left side elevation view, the right side elevation being a mirror image thereof;

FIG. 14 is a top, front and right side perspective view of a third embodiment of a divided food dish showing my new design;

FIG. 15 is a bottom, rear and right side perspective view thereof;

FIG. 16 is a top plan view thereof;

FIG. 17 is a bottom plan view thereof;

FIG. 18 is a front elevation view, the rear elevation being identical thereto; and,

(Continued)

FIG. 19 is a right side elevation view, the left side elevation being identical thereto.
